(57) **CLAIM**

The ornamental design for a universal mount for wireless phones, as shown and described.

DESCRIPTION

FIG. 1 is a perspective view of the present invention.

FIG. 2 is a front view of the present invention.

FIG. 3 is a left side view of the present invention.

FIG. 4 is a right side view of the present invention.

FIG. 5 is a top view of the present invention.

FIG. 6 is a bottom view of the present invention.

FIG. 7 is a back view of the present invention.

FIG. 8 is a perspective view of the present invention shown in use; and,

FIG. 9 is a right side view of the present invention shown in use.

The broken line showings in FIGS. 8 and 9 are for illustrative purposes only and forms no part of the claimed design.
